US00D543846S

(12) **United States Design Patent** (10) **Patent No.:** **US D543,846 S**
Kitamura et al. (45) **Date of Patent:** **** Jun. 5, 2007**

(54) **BOTTLE**

GB 2099463 5/2001

(75) Inventors: **Nobuyuki Kitamura**, Yahata (JP);
Shinsuke Nomura, Kyoto (JP)

* cited by examiner

(73) Assignee: **The Procter & Gamble company**,
Cincinnati, OH (US)

Primary Examiner—Ian Simmons
Assistant Examiner—Dana L. Sipos

(**) Term: **14 Years**

(74) *Attorney, Agent, or Firm*—Jeffrey V. Bamber; Laura R. Grunzinger

(21) Appl. No.: **29/244,543**

(57) **CLAIM**

(22) Filed: **Dec. 8, 2005**

The ornamental design for a bottle, as shown and described.

(30) **Foreign Application Priority Data**

Jun. 17, 2005 (GB) 3021595

DESCRIPTION

(51) **LOC (8) Cl.** **09-01**

FIG. 1 is a perspective view of a bottle, embodying our new design;

(52) **U.S. Cl.** **D9/500**

FIG. 2 is a front view thereof;

(58) **Field of Classification Search** D9/443,

FIG. 3 is a back view thereof;

D9/449, 452–454, 500, 502–504, 516, 529,
D9/537–540, 549, 557–558, 776–778; D7/509–511,
D7/523, 532–533, 590–591, 596–597; 215/379–384;
220/660–662, 669, 675–676

FIG. 4 is a top plan view thereof;

See application file for complete search history.

FIG. 5 is a bottom view thereof;

(56) **References Cited**

FIG. 6 is a left side view thereof; and

U.S. PATENT DOCUMENTS

FIG. 7 is a right side view thereof.
